UNITED STATES PATENT OFFICE.

SAMUEL MARCUS, OF BROOKLYN, NEW YORK, ASSIGNOR TO F. & M. NOVELTY CO. INC., OF NEW YORK, N. Y., A CORPORATION OF NEW YORK.

ARTIFICIAL EYES FOR DOLLS, DISPLAY FIGURES, AND THE LIKE.

Application filed December 31, 1918, Serial No. 269,082. Renewed April 8, 1922. Serial No. 550,794.

To all whom it may concern:

Be it known that I, SAMUEL MARCUS, a citizen of the United States, and a resident of Brooklyn, in the county of Kings and State of New York, have invented certain new and useful Improvements in Artificial Eyes for Dolls, Display Figures, and the like, of which the following is a specification.

10 The invention relates to improvements in the manufacture of eyes for dolls and other purposes, such as display-figures, and the invention has several purposes in view, one being to produce a novel eye, another to provide novel means for connecting and mounting in the head of the doll a pair of eyes and another being to furnish novel cooperative means for permitting the eyes to turn up and down and also laterally, so that the 20 eyes may have a substantially universal movement during the handling of the doll. A further purpose of the invention is to provide proper eyelids for the eyes, with means for assuring their turning up and 25 down during the handling of the doll. The eye itself, apart from the means by which the eyes may be connected up and secured within the head of a doll, comprises an inner hollow shell, preferably of metal, having 30 a flat front surface bearing an imitation of the iris of an eye and an exterior or outer substantially hemispherical shell of transparent celluloid or like material applied over and enclosing the metal shell. The 35 pair of eyes may be so connected up as to roll to closed position when the doll is turned from a vertical to a horizontal position and also to roll to open position when the doll is turned from a horizontal to a 40 vertical position, and also to roll laterally in either direction according to the position which may be given to the doll.

The invention and suitable mechanisms for carrying the same into effect, will be 45 fully understood from the detailed description hereinafter presented, reference being had to the accompanying drawings, in which:

Fig. 1 is a vertical section through the 50 face of a doll and eye mechanism embodying the essential features of my invention; Fig. 2 is a front elevation of the eye features of my invention, shown on an enlarged scale, and detached from the inner surface 55 of the doll's face;

Fig. 3 is a top view of the doll's eye mechanism shown in Fig. 2;

Fig. 4 is a sectional view through the same, taken on the dotted line 4—4 of Fig. 2, the eyes however being shown as turned laterally from the front position indicated in Fig. 3;

Fig. 5 is a vertical central section, partly broken away, through one of the eyes taken on the dotted line 5—5 of Fig. 3;

Fig. 6 is a perspective view of the inner hollow shell embraced in each of the eyes and having a flat front bearing an imprint of the iris of the eye;

Fig. 7 is a corresponding view of the 70 outer transparent celluloid or like cap-material shell closely applied upon the inner shell shown in Fig. 6, but of convex outline and not fitting against said flat front of said shell indicated in Fig. 4;

Fig. 8 is a rear elevation, partly broken away, of one of the eyes and connecting bar;

Fig. 9 is a horizontal section through the mechanism connected with the eyes taken on the dotted line 9—9 of Fig. 3;

Fig. 10 is a vertical section corresponding with Fig. 1 through a portion of my invention, the eyelids for the doll and some other features hereinafter referred to being omitted;

Fig. 11 is a front view of the mechanism shown in Fig. 10 detached from the head of the doll, and

Fig. 12 is a top view, on a large scale, illustrative of the mechanism shown in Figs. 10 and 11.

In the drawings, 15 indicates the face portion of the head of an ordinary doll, and 16, 17 indicate, respectively, the right eye and left eye for the doll. The eyes 16, 17 are of substantially corresponding construction, and each eye has an inner substantially hemispherical metal shell 18 having a flat front surface 19 bearing an imprint 20 representing the iris of an eye. The 100 metal shell 18 is slotted at its inner edge, as at 21, to receive the end portion of the bridge or connecting bar 22. Each of the eyes is also formed with an outer substantially hemispherical transparent celluloid shell 23, 105 which closely fits upon the metal shell 18, with the exception that at its front said shell 23 is convex, thereby leaving a space, which I number 24, between the front of the shell 23 and the flat front 19 of the shell 110.

18. The shell 23 is slotted at its inner edge, as at 25, to match the slot 21 in the shell 18, and thereby provide means for the reception of the end portion of the cross-bar 5 22. Each eye is provided with an inner vertical bar or post 26 which has a small recess in its upper and also in its lower end, into which recesses upper and lower edge portions of the metal shell 18 are depressed 10 or indented, as shown in Fig. 5, whereby the post 26 becomes pivotally and permanently mounted within the metal shell 18. The posts 26 of the eyes 16, 17 are horizontally apertured to receive the ends of the bridge 15 or cross-bar 22 and each post is provided with a set-screw 27 adapted to pass horizontally into the same and engage the end portion of the cross-bar 22, whereby said bar 22 becomes connected with and connects the 20 pair of eyes 16, 17. The set-screw 27 admits of the angular adjustment of the eyes on the cross-bar 22 so as to adapt said eyes for correct position in the head of a doll notwithstanding some irregularities that 25 may happen to be in said head. The pivot posts 26 admit, on and due to the rotary movement of the pivotally mounted bridge 22, an up and down rolling movement of the eyes under changes in the position of 30 the doll and being by preference pivotally connected with the shells 18 of the eyes, also admit of the eyes having a lateral or sideways turning movement under certain positions that may be given to the doll. The 35 posts 26 also materially strengthen the eyes and thus prevent the same from being injured by rough handling of the doll. The posts 26 and screws 27 also admit of the lateral adjustment of the eyes 16, 17 on the 40 bridge or cross-bar 22, and this is sometimes of importance in enabling the eyes to be adjusted to meet the locations of the openings in the face of the doll for the eyes. The bridge or cross-bar 22 is pivotally 45 suspended in ears 28 formed at opposite side edges of the lower portion of a metal plate 29 whose upper end is fastened by shellac or other suitable substance 30 to the inner surface of the forehead of the doll's 50 face above the eye-sockets, and hence said cross-bar 22, posts 26 and the eyes connected therewith may have a movement permitting the eyes 16, 17 to roll upwardly or downwardly. 55 The metal shells 18 of the eyes 16, 17 are respectively formed with or have secured thereto rearwardly projecting arms 31 which are rigid with the shells 18 and extend rearwardly and one arm 31 is pivotally connected with one member 32 of a transverse bar comprising said member 32 and a member 33, which is pivotally connected with the other arm 31. The member 33 is formed with a clasp 34 which engages the member 32 and permits of the adjustment of the 60 members 32, 33 toward and from each other as the requirements may demand, there being sufficient frictional engagement of the clasp 34 with the member 32 to maintain said members in their adjusted relation and this 70 friction being increased when necessary by flattening the clasp 34 on said member 32. The member 33 is provided with a weight 35. Since the two eyes are pivotally mounted on the posts 26 and provide the 75 arms 31 connected by the transverse bar formed of the members 32, 33, and since one of said members is equipped with the weight 35, it results that the eyes may have a lateral movement to one side or the other 80 according to the position given to the doll, the weight 35, with its connecting mechanism, serving to turn the eyes in one direction when the doll is turned to one side and in the other direction when the doll is 85 turned to the other side. I provide the metal eye-members 18 with rearwardly extending arms 36 which may be bent down against and secured to the posts 26 as indicated by the dotted lines in Fig. 8, when 90 it is not desired that the eyes 16, 17 should have a sidewise or lateral movement. When the arms 36 are fastened against the posts 26, the eyes 16, 17 may have a downward and upward rolling motion, according to 95 usual custom, but will be prevented from having side-wise or lateral motion, such as represented in Fig. 4. The bridge or cross-bar 22 passes through 100 elongated openings in the ears 28, as shown in Figs. 1, 4 and 10, and the plate 29, on which said ears 28 are formed, is provided with a spring having two legs 37 whose lower ends bear against the bridge or cross-bar 22 and tend to bind the eyes 16, 17 carried by said bar against the eye-sockets formed in the face of the doll, thereby maintaining the eyes in proper relation to said sockets. The elongation of the openings in 105 the ears 28 through which the bridge or cross-bar 22 passes, permits said bar, with the eyes carried thereby, to yield rearwardly to any irregularity or lack of uniformity in the surfaces surrounding the eye-sockets of the doll's face, and this I regard as a feature of importance, since dolls' faces are sometimes irregular around the eye sockets due to defects or irregularities in the manufacture of the doll's head. The elongated 110 openings in the ears 28 combined with the spring legs 37 perform the desirable function of adapting the eyes to irregularities in the eye sockets of the doll's face and also to maintain the eyes in correct relation to the eye sockets. 115 The eyes 16, 17 may, in one embodiment of my invention, be provided with metal eye-lids 38, which are of arcuate outline and closely arranged against the upper portions of said eyes and have arms 39 which extend 120

125 130

downwardly and forwardly and are apertured to receive the end portions of the bridge or cross-bar 22, whereby said eye-lids 38 become pivotally mounted on said bridge 5 or cross-bar. When the eye-lids 38 are employed, the actuating weight 40 for rolling the eyes and said lids will be connected by arms 41 with the rear edge portions of said lids, so that when the doll is caused to recline, the weight 40 may swing inwardly and act to close the lids 38 downwardly over the eyes and also so that when the doll is lifted up, the weight 40 will swing towards the inner surface of the face of the doll and 10 act to turn the lids 38 to open position. The weight 40 may be provided with a pad 14 to cushion the blow of the weight 40 against the face of the doll.

The weight 40 in the construction shown 20 in Figs. 1 to 4 inclusive also serves as means for causing the eyes 16, 17 to roll downwardly or upwardly in accordance with the position given to the doll, and in carrying out this feature of the operation I rigidly 25 secure on the bridge or cross-bar 22 a wire member 42 which normally extends downwardly and forwardly from said bridge or cross-bar toward the face of the doll and has a rearwardly extending arm 43 equipped 30 with a hook member 44, which passes between the arms 41 connected with the weight 40 and is adjacent to the crotch 45 where said arms 41 come together and thence extend downwardly to the weight 40, as shown in 35 Figs. 1 and 2. When the doll is reclined so that the weight starts rearwardly or in that case downwardly from the face of the doll, said weight will first operate to partly turn the lids 38 to closed position, and then when 40 the adjoining portions of the arms 41 reach and act against the hook 44 of the arm 42, the weight 40 will, through said arm 42 and bridge or cross-bar 22, operate to roll the eyes 16, 17 downwardly. When the doll is 45 restored to vertical position, the weight 40 and its connections serve to move the lids 38 to open position, and the weight 40 and its connections also serve to assist the eyes in having their upward rolling motion or to 50 open position.

I do not limit my invention to the presence of the eye-lids 38, since these eye-lids may not be desired by all manufacturers of dolls owing to the fact that they add to the 55 expense of the eye equipment.

When I do not wish to apply the eye-lids 38 to the eyes, I utilize the construction shown more particularly in Figs. 10 and 11 in which all of the features of the construction shown in Fig. 2 are employed, with the exception of the eye-lids, the arm 42 and the arms 41 suspending the weight 40, and in lieu of connecting the weight, which in Figs. 10 and 11 I number 46, with eye-lids, 60 I connect the same directly and rigidly by

a rod 47 with the bridge or cross-bar 22, in which construction, the weight acts through the cross-bar 22 to cause the eyes 16, 17 to perform their upwardly and downwardly rolling motion in a manner well understood. 70

The separation of the convex front of the outer shell 23 from the flat front of the inner body of the eye bearing the imprint of an iris adds greatly to the appearance of the 75 eye when positioned in a doll's head, and said body around the iris will be coated white.

I therefore do not limit my invention to all of the details of form and construction 80 illustrated, since it is obvious from the foregoing description that many of these details may be modified without departure from my invention.

What I claim as my invention and desire to secure by Letters Patent, is:

1. A pair of eyes for a doll and the like, a bridge connecting the eyes, a plate supporting said bridge and to be fastened to the inner front surface of the doll's head, 90 and a spring secured on said plate and engaging said bridge in a direction to yieldingly press the eyes against the eye-sockets, said bridge being adapted to have a partial rotary movement and also to have movement toward and from the front of the doll's head independently of said plate. 95

2. A pair of eyes for a doll, a plate to be fastened to the inner surface of the doll's head, means connecting said eyes and pivotally mounted on said plate and supporting the eyes therefrom, and a spring secured on said plate and engaging said supporting means in a direction to yieldingly press the eyes against the eye-sockets, said 100 supporting means being adapted to have a partial rotary movement, being pivotally secured, and also to have movement toward and from the front of the doll's head independently of said plate. 105

3. A pair of eyes for a doll and the like, a bridge connecting the eyes, a plate holding said bridge and being adapted to be fastened to the inner surface of the doll's head, and a spring mounted on said plate 115 and engaging said bridge in a direction to press the eyes against the eye-sockets, said plate having ears containing elongated openings through which said bridge passes. 110

4. A pair of eyes for a doll and the like, 120 a bridge connecting the eyes, a plate having elongated openings through which the bridge freely passes and which plate is adapted to be fastened to the inner surface of the doll's head, and a spring mounted on 125 said plate and having legs engaging said bridge at each side of the center thereof in a direction to yieldingly press the eyes against the eye-sockets.

5. A pair of eyes for a doll and the like, 130

4

said eyes comprising inner and outer substantially hemispherical shells recessed at their inner facing side portions, vertical posts secured at their upper and lower ends within said inner shells and having transverse openings and thereat set-screws, a bridge extending through said recesses and said openings and secured to said posts by said screws, means for pivotally supporting said bridge within the doll's head, and a weight for turning said bridge on its longitudinal axis to effect the rolling motion of the eyes.

6. A pair of eyes for a doll and the like, said eyes comprising inner and outer substantially hemispherical shells recessed at their inner facing side portions, vertical posts pivotally secured at their upper and lower ends within said inner shells, a connecting bridge extending through said recesses and secured at its ends to said posts, means for pivotally supporting said bridge within the doll's head, a weight for turning said bridge on its longitudinal axis to effect an up and down rolling motion of the eyes, and means for effecting a lateral motion of the eyes comprising arms connected with said inner shells, a bar pivoted at its ends to said arms and a weight on said bar.

7. A pair of eyes for a doll and the like, said eyes comprising inner and outer substantially hemispherical shells recessed at

their inner facing side portions, vertical posts pivotally secured at their upper and lower ends within said inner shells, a connecting bridge extending through said recesses and secured at its ends to said posts, means for pivotally supporting said bridge within the doll's head, a weight for turning said bridge on its longitudinal axis to effect an up and down rolling motion of the eyes, and means for effecting a lateral motion of the eyes comprising arms connected with said inner shells, a bar pivoted at its ends to said arms and a weight on said bar, and said bar comprising members which are adjustable on each other whereby to regulate the length of the bar.

8. A pair of eyes for a doll and the like, a bridge connecting the eyes, a plate having elongated openings through which the bridge freely passes and which plate is adapted to be fastened to the inner surface of the doll's head, and a spring mounted on said plate and engaging said bridge at each side of the center thereof in a direction to yieldingly press the eyes against the eye-sockets.

Signed at New York city, in the county of New York and State of New York, this 30th day of December, A. D. 1918.

SAMUEL MARCUS.
